ATTACHMENT FOR BUTTONHOLES

Charles William Jepson, Ridlonville, Maine

Application April 15, 1955, Serial No. 501,509

5 Claims. (Cl. 24—202)

This invention relates to buttonholes for garments, fabrics and the like, and more particularly to an attachment for such buttonholes.

The object of the invention is to provide an attachment for buttonholes whereby such buttonholes will be reinforced and whereby the attachment can be placed on new or used articles of clothing.

Another object of the invention is to provide a buttonhole attachment which is adapted to be secured in and around a buttonhole whereby tearing or damage to the buttonhole from usage will be minimized or prevented since the present invention will help to reinforce the buttonhole.

A further object of the invention is to provide a buttonhole attachment which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a fragmentary elevational view illustrating the attachment of the present invention in use with a buttonhole of a garment or the like.

Figure 2 is a sectional view taken on the line 2—2 of Figure 1.

Figure 3 is a top plan view of the buttonhole attachment removed from the garment or fabric.

Figure 4 is a sectional view taken through the buttonhole attachment, and showing a modification wherein a spring member is used for helping to maintain the parts in their proper position.

Figure 5 is a view similar to Figure 1 but illustrating a modification wherein rivets or the like are used for securing the attachment in place instead of stitching.

Figure 6 is a sectional view taken on the line 6—6 of Figure 5.

Referring in detail to the drawings, the numeral 10 designates a portion of a garment or fabric which is provided with one or more buttonholes 11, and the present invention is directed to an attachment which will reinforce the buttonhole 11 so as to minimize or prevent tearing or damage thereto during use.

The attachment of the present invention includes a body member which is indicated generally by the numeral 12, and the body member 12 can be made of any suitable material. The body member 12 includes a pair of spaced parallel side sections 14 which are arranged on opposite sides of the fabric 10, and the side sections 14 may be interconnected together by means of an arcuate section 15, Figure 2. The body member 12 is shaped to include a first or major portion 16, and extending from the first portion 16 is a pair of enlarged tabs or flaps 17. The tabs 17 are provided with opposed or registering apertures or openings 18, and stitching 19 extends through the apertures 18 and through the fabric 10 for securing the body member 12 in place on the fabric 10. Instead of using

2

the stitching 19, rivets such as the rivets 20 shown in Figures 5 and 6 can be used.

The body member 12 further includes curved end portions 21 which terminate in fingers 22 that are tapered so that there may result a saving of material, and the free ends of the fingers 22 may be spaced from each other and may be somewhat pointed. The fingers 22 are arranged on the opposite side of the buttonhole 11 from the tabs 17.

There is further provided a support member which is indicated generally by the numeral 23, and the support member 23 and body member 12 can be made of any suitable material. The support member 23 includes a pair of spaced apart side walls 24 which are arranged on opposite sides of the fabric 10, and the side walls 24 are interconnected together by means of an arcuate or curved wall section 25 which extends through the buttonhole 11. The side walls 24 are each provided with a plurality of spaced apertures 26 which extend along their longitudinal free edges, and stitching 27 may extend through the apertures 26 and through the fabric 10 for securing the support member 23 in place. The support member 23 thus serves to clamp or maintain the fingers 22 in their proper position. Thus, it will be seen that the walls of the fabric 10 which define the buttonhole 11 are completely enclosed or surrounded by the attachment of the present invention so that tearing or other damage to the buttonhole or fabric will be prevented. Instead of using the stitching 27, rivets 20 can be extended through the openings 26 as shown in Figure 5 for securing the support member 23 to the fabric 10. If desired a spring member 28 may be arranged in engagement with the attachment as shown in Figure 4, and the spring member 28 helps to reinforce and maintain these parts in their proper assembled relation.

From the foregoing it is apparent that there has been provided an attachment for use with buttonholes such as the buttonhole 11. In use the body member 12 can be connected to the fabric 10 in any suitable manner, as for example by means of the stitching 19 or by means of the rivets 20. The body member 12 is arranged so that the side sections 14 are arranged on opposite sides of the fabric 10, and the fingers 22 are positioned as shown in Figure 1. Then, the support member 23 is secured in place by means of the stitching 27 or rivets 20, and the support member 23 will retain the fingers 22 in place. Thus, all portions of the fabric which surround the buttonhole 11 will be covered by the attachment of the present invention so that as the button is moved through the buttonhole, the buttonhole will not tear or become accidentally enlarged. If desired the spring member 28 can be arranged in engagement with the parts as shown in Figure 4 so as to help retain the parts in their proper assembled position.

Any suitable means can be used for securing the support member and body member in place, as for example brads can be used, and the support member and body member can be made of any suitable material and in any desired size. With the present invention the buttonhole will be reinforced so that the ends will not become torn or unduly strained. However, the attachment will yield sufficiently to permit the button to be inserted into the buttonhole. Thus, the support member and body member may be made of material which yields slightly. The free ends or fingers 22 can move slightly to provide the assembly with sufficient flexibility to permit a button to be inserted into the buttonhole or removed therefrom.

I claim:

1. In an attachment for a buttonhole formed in a fabric or the like, a body member including a pair of spaced parallel side sections arranged on opposite sides of the fabric, an arcuate section interconnecting said side sections together, said body member including a first portion, a pair of spaced apart tabs extending outwardly from said

first portion and said tabs being provided with a plurality of registering apertures, securing means extending through said registering apertures, curved portions extending outwardly from the ends of said first portion, said curved end portions terminating in inwardly extending tapered fingers, the free ends of said fingers being pointed and arranged on the opposite side of the buttonhole from said tabs, and a support member including a pair of spaced parallel side walls arranged on opposite sides of the fabric and surrounding a portion of said fingers and extending outwardly of said fingers, a curved wall section interconnecting the side walls of said support member together, there being a plurality of opposed apertures in said side walls, and securing means extending through said last named apertures.

2. The structure as defined in claim 1, and further including a spring member surrounding said buttonhole and arranged in engagement with said body member.

3. The structure as defined in claim 1, wherein said securing means comprises stitching.

4. The structure as defined in claim 1, wherein said securing means comprises rivets.

5. An attachment for a buttonhole formed in a fabric or the like, comprising a body member embodying a pair of spaced parallel side sections arranged on opposite sides of the fabric, an arcuate section interconnecting said side sections together, said body member including a first portion, a pair of spaced apart enlarged tabs extending from said first portion and said tabs being provided with a plurality of registering apertures, securing means extending through said registering apertures, curved portions extending from the ends of said first portion, said curved

end portions terminating in tapered fingers, the free ends of said fingers being pointed and arranged on the opposite side of the buttonhole from said tabs, the free ends of the fingers being able to move slightly so as provide the assembly with sufficient flexibility to permit a button to be inserted into the buttonhole or removed therefrom, a support member including a pair of spaced parallel side walls arranged on opposite sides of the fabric and surrounding a portion of said fingers, a curved wall section interconnecting the side walls of said support member together, there being a plurality of opposed apertures in said side walls, securing means extending through said last named apertures, said support member and body member being made of a material which yields slightly, and a spring member surrounding said buttonhole and arranged in engagement with said body member for helping to reinforce and maintain the parts in their proper assembled positions.
